ASH TRAY

Gustave C. Cattani, San Francisco, Calif.

Application April 8, 1952, Serial No. 19,250

Term of patent 14 years

(Cl. D85—2)

To all whom it may concern:

Be it known that I, Gustave C. Cattani, a citizen of the United States of America, residing in the city and county of San Francisco, State of California, have invented a new, original, and ornamental Design for an Ash Tray, of which the following is a specification, reference being had to the accompanying drawing, forming a part hereof.

Figure 1 is a view in perspective of an ash tray embodying my new design;

Figure 2 is a top plan view;

Figure 3 is a side elevation of the ash tray shown in Figure 1; and

Figure 4 is a sectional view taken along the line 4—4 of Figure 2.

I claim:

The ornamental design for an ash tray, as shown.

GUSTAVE C. CATTANI.
